United States Patent Office.

OTWAY P. HARE, OF PETERSBURG, VIRGINIA.

Letters Patent No. 104,146, dated June 14, 1870.

IMPROVED LINIMENT.

The Schedule referred to in these Letters Patent and making part of the same

To all whom it may concern:

Be it known that I, OTWAY P. HARE, of Petersburg, in the county of Dinwiddie and State of Virginia, have invented a certain new and useful Liniment; and I do hereby declare that the following is a full and exact description thereof.

My invention consists in a liniment adapted to cure rheumatism, neuralgia, nervous headache, and all analogous diseases; and

To enable others to make and use my improved liniment, I will proceed to describe the manner in which it is made and applied.

I start, as a base, with eight ounces of tincture aconite root, to which I add twelve ounces tincture arnica flowers, eight ounces laudanum, (Tr. opii,) eight ounces tincture wild arsenic, eight ounces tincture belladonna leaves, four ounces fluid extract prickly-ash, six ounces pure oil camphor, six ounces cajeput, (pure, only,) and sixteen ounces chloroform; mixing them well and thoroughly together finishes the process of manufacture. The liniment is then bottled and tightly corked.

The quantities above set forth are enumerated merely for the purpose of establishing the proportions, which must be adhered to in large or small quantities.

In order that the liniment should have the desired effect, it must be applied in the following manner:

First, saturate a piece of cloth about the size of the hand with two or three teaspoonfuls of the liniment, covering the side of the cloth next the hand with oil-silk or bladder, and be sure, by pressure, to exclude the air from the part affected. In a few moments it will become warm, and when too hot, rub the parts well until all the liniment shall have been absorbed.

I have found, after long and careful experiment, that the ingredients mixed and applied as set forth produce speedy and perfect cures of the diseases named.

The bottle containing the liniment must always be kept tightly corked, and be well shaken before using.

Having described the manner of making and using my improved liniment,

What I claim as new, and desire to secure by Letters Patent, is—

The liniment composed of tinctures, fluid extract, pure oils, &c., mixed in the proportions, as and for the purposes hereinbefore described.

In testimony whereof I have hereunto set my hand and seal this 9th day of February, A. D. 1870.

O. P. HARE. [L. S.]
